(57) **CLAIM**

The ornamental design for the cassette assembly with tubing loops, as shown and described.

DESCRIPTION

FIG. 1 is a top perspective view of a cassette assembly with tubing loops showing our new design;

FIG. 2 is a bottom perspective view thereof;

FIG. 3 is a front view of the cassette assembly with tubing loops of FIG. 1;

FIG. 4 is a rear view of the cassette assembly with tubing loops of FIG. 1;

FIG. 5 is end view taken from the right-hand side of FIG. 3;

FIG. 6 is an end view taken from the left-hand side of FIG. 3;

FIG. 7 is a top view of the of the cassette assembly with tubing loops of FIG. 1; and,

FIG. 8 is a bottom view of the of the cassette assembly with tubing loops of FIG. 1.

The broken lines in the drawing views are included for the purpose of illustrating portions of the cassette assembly with pump tubing that form no part of the claimed design.
